(57) CLAIM

(21) Appl. No.: **29/166,829**

The ornamental design for a non-rotating centerpiece for wheel, as shown and described.

(22) Filed: **Sep. 4, 2002**

DESCRIPTION

(51) LOC (7) Cl. **12-16**

FIG. 1 is a front elevational view of a non-rotating centerpiece for wheel showing my new design;

(52) U.S. Cl. **D12/213**

FIG. 2 is a rear elevational view thereof;

(58) Field of Search **D12/207, 213,**

FIG. 3 is a side view, taken from the left side of FIG. 1, the right side view being a mirror image thereof; and, FIG. 4 is a top plan view thereof; the bottom plan view being a mirror image thereof.

D12/400, 204; 301/37.43, 37.374, 37.101,

105.1, 108.1-108.4; D8/397; D9/435

(56) References Cited

The broken lines showing lettering and a wheel cover in FIG. 1 is for illustrative purposes only and forms no part of the claimed design.
